JAMES F. L. MARREN, OF PHILADELPHIA, PENNSYLVANIA

PNEUMATIC LOCKING INFLATING TUBE FOR INFLATABLE BODIES

Application filed September 19, 1930. Serial No. 483,083.

This invention relates to an improved pneumatic locking inflating tube for inflatable bodies, volley balls, punching bags, footballs, play balls, seat cushions and the like, and especially where the inflatable body has a single casing though it may include a cover or protecting skin for the body, and it is the purpose of the present invention to form a chamber adjacent the interior surface 10 of the inflatable body, adapted for the reception of an inflating tube communicating with the interior of the inflatable body at one end and having a flat extremity at its other end, to be withdrawn through an opening in the 15 wall of the inflatable body so that the inflating tube can be untwisted to allow the body to be inflated, so that after the body is inflated the tube can be twisted again and the flat end drawn back into the chamber, therefore locking the tube and preventing escape of 20 the air.

Another purpose is to provide, in an article of manufacture of this kind, an inflatable body which is perfectly smooth and unobstructed on its outer surface, due to the inflating tube being housed in a chamber on the inner surface of the inflatable body, in such wise as to cause no bulging of the wall of the body, thereby preventing the inflatable body if in the form of a foot or play ball, from rebounding at different angles, in case the ball should contact with the surface at a point where the inflating tube may be located.

Another purpose is to provide a housing chamber on the inner surface of an inflatable body for encasing a twisted inflating tube, the latter having a flat end positioned within the chamber, to prevent the inflating tube from untwisting, and hence preventing the escape of air.

It is to be understood that the particulars herein given are in no way limitative, and that while still keeping within the scope of the invention, any desired modification of details and proportions may be made in the construction of the appliance according to circumstances.

The invention comprises further features 50 and combination of parts to be hereinafter

set forth, shown in the drawing and claimed.

In the drawing:—

Figure 1 is a view of a football, showing the usual outer section of leather, showing the usual laced opening for permitting access to 55 the inner inflatable body for inflating the same.

Figure 2 is a sectional view on line 2—2 of Figure 1.

Figure 3 is a view of a ball of an inflated 60 character, showing an elongated slot for permitting access to an inflating tube encased in a chamber formed on the inner surface of the wall of the ball.

Figure 4 is a sectional view on line 4—4 of 65 Figure 3.

Figure 5 is a cross sectional view on line 5—5 of Figure 4.

Figure 6 is a view in perspective of a pneumatic cushion or seat, partly broken away, 70 showing the improved pneumatic locking inflating tube as applied.

Referring to the drawing, 1 identifies an inflatable body, which may or may not be encased in an outer skin 2, as shown in Figures 75 1 and 2, provided the body is to be used as a football.

Regardless of whether or not the inflatable body 1 is to be encased, it is provided with a chamber 3 adjacent the interior surface of 80 the wall of the body. This chamber is caused to be formed by means of a patch 4, which may be fastened in any suitable manner at 5 to the inner surface of the body 1, for example a vulcanized fastening may be 85 used as a practical and substantial way of fastening the patch piece 4 in position.

The chamber 3 is adapted for housing a rubber inflating tube 6, one end 7 of which is fastened at 8 by vulcanizing to one end of the patch piece 4. The end 7 of the inflating tube, though it is fastened to the patch piece 4, communicates with the interior of the inflatable body 1, so that air under pressure may 95 be forced through the tube 6 for inflating the body.

The inflating tube at its other end terminates in a nozzle 9, which is more or less flattened and is provided with a passage 10 com- 100

municating with the interior of the inflating tube 6.

When the inflatable body is in its deflated condition, the wall of the body can be pinched up sufficiently to permit the flattened nozzle 9 (which may be constructed of any suitable material, preferably hard rubber) to pass through the opening 11 of the wall of the inflatable body 1. The flattened nozzle 9 protrudes sufficiently beyond the wall of the body 1 to allow it to be inserted in a person's mouth, whereby air may be forced into the body. After the body has been inflated sufficiently, the flattened nozzle may be turned over and over again sufficiently to impart a twist in the inflating tube, and as the tube twists, it starts to shorten or rather contract, and during this shortening or contracting process the flattened nozzle is drawn back through the opening 11; so that the nozzle will lie in the narrow chamber 3. The twisting action of the inflating tube tends to draw the flat nozzle through the opening and into the chamber, and since the body is inflated and the chamber being of a narrow shape, at least one-half the width of the nozzle, it is obvious that the nozzle cannot turn in the chamber, therefore the inflating tube is prevented from untwisting, which in turn prevents the escape of air contained in the body 1.

Where the opening 11 is formed in the wall of the inflatable body and around the opening, the wall of the inflatable body is more or less thickened or reinforced as shown at 35 12 to strengthen the marginal edges of the opening, and thereby preventing the same from unnecessarily tearing or otherwise rupturing.

As shown in Figure 6, the flat nozzle 9 is 40 provided with a threaded extension 13, which includes an inflating valve 14. This threaded extension and inflating valve 14 is provided for the purpose of attaching the usual rubber hose of a pneumatic pump, so that in 45 case the inflatable body in Figure 6 be of a size equal to a mattress, so that such proportion of inflatable body can be inflated more conveniently and with greater ease, than where you insert the nozzle 9 in the mouth 50 for inflating footballs, play balls and the like.

The preventing of the untwisting of the inflating tube 6 is accomplished due to the fact that the nozzle 9 is relatively flat, and that the pressure of air on the interior of the 55 inflatable body presses the opposite walls of the chamber toward each other. In other words, the pressure of air is such as to force the patch 4 toward the wall of the inflatable body. This action is an obvious result derived from the structure shown and described.

The invention having been set forth, what is claimed is:

1. An inflatable body having a single wall 60 and provided with a flattened elongated

chamber immediately adjacent its interior surface, an inflating tube housed in said chamber with one end fastened to one of the end walls of said chamber and communicating with the interior of the body, the other end of the chamber having an elongated outlet opening and through which the inflating tube is adapted to extend, said tube adapted to be twisted to perform the double function of preventing escape of air from the body and drawing the end of the tube back into the chamber, and means on the drawn-in end of the tube to cooperate with the walls of the chamber to prevent the tube from untwisting. 75

2. An inflatable body having a single wall 80 and provided with a flattened elongated chamber immediately adjacent its interior surface, an inflating tube housed in said chamber with one end fastened to one of the end walls of said chamber and communicating 85 with the interior of the body, the other end of the chamber having an elongated outlet opening and through which the inflating tube is adapted to extend, said tube adapted to be twisted to perform the double function of preventing escape of air from the body and drawing the end of the tube back into the chamber, and a flattened nozzle on the drawn-in end of the tube for lying between the walls 90 of the chamber, thereby preventing the inflating tube from untwisting. 95

3. The combination with an inflatable body having a single wall, of an elongated relatively flat chamber adjacent the inner surface of the wall, an inflating tube twisted and located in said chamber with one end connected to one of the end walls of the chamber and communicating with the interior of the body, and means at the other end of the inflating tube located between the opposing walls of 100 the chamber to prevent the inflating tube 105 from untwisting.

4. The combination with an inflatable body having a single wall, of an elongated relatively flat chamber adjacent the inner surface 110 of the wall, an inflating tube twisted and located in said chamber with one end connected to one of the end walls of the chamber and communicating with the interior of the body, and means at the other end of the inflating tube located between the opposing walls of the chamber to prevent the inflating tube from untwisting, the other end of the chamber having an elongated opening through which said holding means may be inserted and positioned on the exterior of the body to allow the inflating tube to be 115 untwisted. 120

5. As an article of manufacture, an inflatable body having a single wall and an elongated chamber on its interior surface, an inflating tube housed in said chamber, one end of the chamber having an outlet opening formed in said wall connected to the inflating tube, which in turn communicates with the 125 130

interior of the inflatable body, the other end of the chamber having an elongated opening, one end of the inflating tube being free and unattached, and means carried by the free 5 and unattached end and engageable within the chamber to prevent the tube from untwisting, said means adapted to be withdrawn through the elongated opening to permit of inflation, the contracting of the inflating tube 10 as it is twisted constituting means to draw said last mentioned means back into the chamber.

6. As an article of manufacture, an inflatable body having a single wall and an elongated chamber on its interior surface, an inflating tube housed in said chamber, one end of the chamber having an outlet opening formed in said wall connected to the inflating tube, which in turn communicates with the 15 20 interior of the inflatable body, one end of the inflating tube being free and unattached, and a flattened nozzle at the free and unattached end engageable between the walls of the chamber to prevent the inflating tube from 25 untwisting, said nozzle adapted to pass through the elongated opening for inflating the body, the twisting of the inflating tube constituting means to draw the nozzle through the elongated opening.

30 7. As an article of manufacture, an inflatable body having a single wall provided on its interior surface with a chamber, a pneumatic twisted inflating tube in the chamber communicating with the interior of the inflatable body, and one end of the inflating tube 35 terminating in means lying flat in said chamber to prevent the inflating tube from untwisting.

8. As an article of manufacture, an inflatable body having a single wall provided on its interior surface with a chamber, a pneumatic twisted inflating tube in the chamber communicating with the interior of the inflatable body, and means to prevent the inflating 45 tube from untwisting, said last named means comprising a flattened nozzle to be positioned flat-wise in said chamber.

9. As an article of manufacture, an inflatable body having a single wall provided on its interior surface with a chamber, a pneumatic twisted inflating tube in the chamber communicating with the interior of the inflatable body, the inlet end of the inflating tube terminating in means lying flat in said 55 chamber to prevent the tube from untwisting, said wall of the inflatable body adjacent one end of the chamber having an expandible opening to permit access to the nozzle, whereby the tube can be untwisted.

60 In testimony whereof I affix my signature.
JAMES F. L. MARREN.
